UMBRELLA

Haig Simonian, North Hollywood, Calif.

Application August 16, 1946, Serial No. 691,050

6 Claims. (Cl. 135—20)

1

This invention relates to umbrellas, parasols, sun-shades and the like.

The principal object of the invention is to provide an umbrella characterized by the elimination of the projections or rib tips at the periphery of the opened umbrella by which, in umbrellas heretofore made, the fabric is secured to the ribs of the frame. An allied object is to devise an umbrella as described in which the end portions of the fabric is not secured to the ribs, i. e., at the rib tips; instead, the securement is made at the peripheral portions of the fabric between the ribs. A further allied object is to provide an umbrella as described in which the said fabric securement is continuous around the periphery of the opened umbrella.

A further object of the invention is to provide a continuous peripheral fabric securement as described which will improve the appearance of the novel umbrella both in its opened and closed conditions. In this aspect, the aforementioned rib projections or rib tips of prior devices detract from the appearance of the umbrella when closed as well as when open. Moreover, such projections of the open umbrella are hazardous in that they present unprotected points; and in the closed umbrella the projecting ends of the ribs are frequently caught on various items, such as clothing in a closet, leading to damage either to the umbrella or to the clothing.

A still further object is to provide a continuous peripheral securement as described which will permit the umbrella to be easily closed without interfering with the folding of the fabric as the ribs are turned inwardly toward the shaft. Another object of the invention is to provide an umbrella having a continuous peripheral fabric securement which will reinforce the fabric at its peripheral portion and which will strengthen the frame, more particularly, its ribs, when open.

For the attainment of the foregoing and such other objects as may appear or be pointed out I have shown several embodiments of my invention in the accompanying drawing, wherein:

Figure 1 is a top view of the improved umbrella in open condition;

Figure 2 is a front view of the umbrella in open condition;

Figure 3 is a front view of the improved umbrella in closed condition;

Figure 4 is a detail, on enlarged scale, of the peripheral securement of the fabric, as seen from the outside of the open umbrella;

Figure 5 is a section close to the rib, taken on the line 5—5 of Figure 4;

2

Figure 6 is a similar section but taken on the line 6—6 of Figure 4, close to the mid point between ribs;

Figure 7 is a detail similar to Figure 4 but showing a modified form of peripheral securement;

Figure 8 is a top view of the hinge joint between peripheral rods; and

Figure 9 is a section taken on the line 9—9 of Figure 7.

10 The novel umbrella has the conventional frame comprising a shaft 9 at the exposed end of which is secured a handle 8 and at the other end of which, covered by umbrella fabric 10, is hinged the plurality of ribs 7. On shaft 9 is slider 6 connected to ribs 7 by stretchers 5 the ends of which are hinged to slider 6 and to intermediate points of the ribs respectively.

As best shown in the preferred structure of Figure 4, fabric 10 of the improved umbrella is not secured to ribs 7. Umbrella fabric 10 is secured, at its peripheral edge, to a plurality of short rods 20 of equal lengths which circumscribe and define the perimeter of the open umbrella, as seen in Figure 1. It will be observed from the latter figure that two rods 20 are disposed in each arcuate portion of the perimeter between ribs, so that the number of rods 20 is twice the number of ribs 7. For convenience in reference, four consecutive rods have been identified in Figure 1 as A, B, C and D. Rods B and C are disposed in an arcuate perimetric portion between adjacent ribs, while rods A and B are disposed on either side of one of the ribs, rods C and D being disposed on either side of the other rib. The adjacent ends of each pair of rods, e. g., B and C, between adjacent ribs are articulated together, at Y, Figure 1, while the adjacent ends of each pair of rods, e. g., A and B, on either side of a rib are articulated together and to the common rib, at X.

40 One form of articulation of the rods 20 at a rib 7 (articulation X) is shown in enlarged detail in Figures 4 and 5. Articulation of the ends of two adjacent rods 20 (rod A and rod B) to one another and to the common rib 7 is made through the

45 medium of a T-shaped link element 30, the stem 32 of which is secured at the end of rib 7 to dispose its crosspiece 31 beyond the end of the rib and normal thereto. Stem 32 is received within the channel 4 of the rib, the opposite walls of the

50 channel being made somewhat wider at the end portion of the rib and the excess width folded or crimped inwardly at 3 to frictionally secure link element 30 at the end of the rib. The ends of rods 20, which are preferably cylindrical, have recessed portions 21, Figure 4, presenting flat sur-

faces 22, see Figure 5; the ends of crosspiece 31 of the T-shaped link element 30 are received in the said end recesses of the adjacent rods (A and B, Figure 4) in abutting relation to the flat surface 22, Figure 5. The rod ends are hinged to the respective ends of crosspiece 31 by pins 24. As clearly shown in Figure 4, the ends of crosspiece 31 are spaced from the recessed shoulders 23 of the rod to provide clearance for turning of the rods about pivot pins 24. The ends of the rods may be rounded, as indicated at 25, Figure 4.

Figure 4 together with Figure 6 also illustrate the form of articulation that would be used at the ends of adjacent rods at the midpoint between ribs. This articulation (Y) is made through the medium of a straight link 41 which is similar in cross-section and length to the crosspiece 31 of the T-shaped link element 30 at articulation X; the ends of straight link 41 is similarly received in recessed portions 21 of the rods and are similarly connected to the rods by pivot pins 24. As a factor in reducing manufacturing costs, the T-shaped link elements 30 may be used at articulation Y as well as at articulation X, so that only one type of link element need be provided. Where the same T-shaped element 30 is employed also at articulation Y, its stem 32 would not be used; because of its short length and inner position the presence of the unused stem would hardly be noticed.

The peripheral rim of cover 10 is secured to the two rods, such as B and C, between adjacent ribs. For this purpose cover 10 is provided along its edge with a plurality of narrow strips 11 each somewhat shorter in length than the rods 20 and separated by open spaces 12 disposed at the rib articulations X and at the midpoint articulations Y. Strips 11 are sufficiently wide so that each can be wrapped tightly about a rod 20 and sewed at the seam 13. Or the strips 11 may be sewed to form looped portions along the periphery of the covering and the rods then inserted therein.

In the open position of the umbrella, as shown in Figure 1 and Figure 2, the rods 20, T-shaped link elements 30, and links 41 form a continuous rim around the umbrella, and lie in a horizontal plane normal to umbrella shaft 9, as viewed in Figure 2. This continuous rim not only affords securement to the umbrella covering 10 and at the same time eliminating rib tips as heretofore used for this purpose, but also reinforces the peripheral edge of the covering. When the umbrella is closed as in Figure 3, rods 20 turn inwardly at their pivot pin articulation to rib elements 30 and at their pivot pin articulation to midpoint links 41, as ribs 7 approach one another and are brought close to shaft 9. In the closed position, rods 20 are more or less parallel to shaft 9 and in close adjacency with one another.

An alternate form of articulating the rods at the ribs 7 (articulation X) and at midpoints between the ribs (articulation Y) and an alternate form of securing covering 10 to the rods are shown in Figures 7-9. In this case 20' are hollow tubes and have central recesses 26 at their ends extending diametrically through the tubes, in which are received the ends of crosspiece 31' of the T-shaped link elements 30' (at rib articulation X) and the ends of straight link 41', the tube and links being connected by pivot pins 24. As in Figures 4-6, stem 32 of T-shaped links 30' is received in channel 4 of rib 7, the end of which is crimped in at 3 to frictionally

secure stem 32. The peripheral edge of covering 10 is formed as strips 14, which are narrower than strips 11 of Figures 4-6, but which are similarly separated by spaces 12 at the ribs (X) and midpoints Y between ribs. Strips 14 have a reinforced or thickened edge 15, and the tubes 20' have a narrow slit 27 extending the length of the tube. Slit 27 is sufficiently wide to permit passage of covering material 10' itself and is too narrow to permit passage of the thickened edge 15. Umbrella covering 10' is secured within the hollow of the tubes 20' by entering the covering material at one end of the tube slit 27 with the thickened edge 15 of the covering passing within the hollow of the tube.

In the above description, the invention has been disclosed merely by way of example and in preferred manner; but obviously many variations and modifications may be made therein which will still be comprised within its spirit. It is to be understood, therefore, that the invention is not limited to any specific form or manner of practicing same, except in so far as such limitations are specified in the appended claims.

25 I claim:

1. An umbrella comprising a predetermined number of channel-shaped ribs, a covering fabric, a plurality of rods twice the said number of ribs arranged about the perimeter of the umbrella with two rods disposed between adjacent ribs, T-shaped link elements each having a stem disposed within the channel at the end of each rib, said rib end being crimped to secure the said element, straight link elements at the midpoint between each pair of adjacent ribs, the ends of said rods being recessed to present a flat surface and a recessed shoulder, the said flat surfaces of the ends of the rods on either side of a rib abutting the end portions of the crosspiece of the said T-shaped link element and the said flat surfaces of the ends of the two rods between adjacent ribs abutting the end portions of the said straight link element at the midpoint between adjacent ribs, pins for pivotally connecting the said flat surfaces of the rods to the said link elements with the said recessed shoulders of the rods sufficiently spaced from the link elements to permit turning of the rods, the peripheral edge of said covering having strips separated by a space at the said ribs and at said midpoints between adjacent ribs, each strip being wrapped about one of said rods and secured by stitching to the covering.

2. An umbrella comprising a predetermined number of ribs, a covering fabric, a plurality of rods twice the said number of ribs arranged about the perimeter of the umbrella with two rods disposed between adjacent ribs, T-shaped link elements each having a stem secured at the end of each rib, straight link elements at the midpoint between each pair of adjacent ribs, the ends of said rods being recessed to present a flat surface and a recessed shoulder, the said flat surfaces of the ends of the rods on either side of a rib abutting the end portions of the crosspiece of the said T-shaped link element and the said flat surfaces of the ends of the two rods between adjacent ribs abutting the end portions of the said straight link element at the midpoint between adjacent ribs, pins for pivotally connecting the said flat surfaces of the rods to the said link elements with the said recessed shoulders of the rods sufficiently spaced from the link elements to permit turning of the rods, the peripheral edge of said covering

being wrapped about the said rods and secured thereto by stitching.

3. An umbrella comprising a predetermined number of channel-shaped ribs, a covering fabric, a plurality of tubes twice the said number of ribs arranged about the perimeter of the umbrella with two tubes disposed between adjacent ribs, T-shaped link elements each having a stem disposed within the channel at the end of each rib, said rib end being crimped to secure the said element, straight link elements at the midpoint between each pair of adjacent ribs, the ends of said tubes being centrally recessed to present a recessed shoulder, the said central recess of the ends of the tubes on either side of a rib receiving the end portions of the crosspiece of the said T-shaped link element and the said central recess of the ends of the two tubes between adjacent ribs abutting the end portions of the said straight link element at the midpoint between adjacent ribs, pins for pivotally connecting the said ends of the tubes to the said link elements with the said recessed shoulders of the tubes sufficiently spaced from the link elements to permit turning of the tubes, the peripheral edge of said covering having thickened strips separated by a space at the said ribs and at said midpoints between adjacent ribs, the said tubes being longitudinally slitted for passage of the said fabric with its said thickened strips disposed within the tubes.

4. An umbrella comprising a predetermined number of ribs, a covering fabric, a plurality of tubes twice the said number of ribs arranged about the perimeter of the umbrella with two tubes disposed between adjacent ribs, T-shaped link elements each having a stem secured at the end of each rib, straight link elements at the midpoint between each pair of adjacent ribs, the ends of said tubes being centrally recessed, the said central recesses of the tubes on either side of a rib receiving the end portions of the crosspiece of the said T-shaped link element and the said central recesses of the two tubes between adjacent ribs receiving the end portions of the said straight link element at the midpoint between adjacent ribs, pins for pivotally connecting the said tubes to the said link elements, the said fabric covering having a thickened peripheral edge, and the said tubes being longitudinally slitted for the said fabric, the thickened peripheral edge of which is received within the tubes.

5. An umbrella comprising a predetermined number of ribs, a covering fabric, a plurality of rods twice the said number of ribs arranged about the perimeter of the umbrella with two rods disposed between adjacent ribs, link elements at each rib and at the midpoint between each pair of adjacent ribs, the ends of said rods being recessed to present a flat surface and a recessed shoulder, the said flat surfaces abutting the end portions of the said link elements, pins for pivotally connecting the said flat surfaces of the rods to the said link elements with the said recessed shoulders of the rods sufficiently spaced from the link elements to permit turning of the rods, the peripheral edge of said covering having looped portions for receiving the said rods.

6. An umbrella comprising a predetermined number of ribs, a covering fabric, a plurality of tubes twice the said number of ribs arranged about the perimeter of the umbrella with two tubes disposed between adjacent ribs, link elements at each rib and at the midpoint between each pair of adjacent ribs, the ends of said tubes being centrally recessed to present a recessed shoulder, the said central recesses receiving the end portions of the said link elements, pins for pivotally connecting the said tubes to the said link elements with the said recessed shoulders of the tubes sufficiently spaced from the link elements to permit turning of the tubes, the peripheral edge of said fabric covering being thickened and the said tubes being longitudinally slitted for passage of the fabric with its thickened peripheral edge received within the tubes.
